UNITED STATES PATENT OFFICE.

HENRY WILHELM, OF ONEIDA MILLS, ASSIGNOR OF ONE-HALF TO BENTON SMITH, OF NEAR MINERVA, OHIO.

GRAIN-SCOURER.

SPECIFICATION forming part of Letters Patent No. 403,020, dated May 7, 1889.

Application filed December 19, 1888. Serial No. 294,042. (No model.)

To all whom it may concern:

Be it known that I, HENRY WILHELM, a citizen of the United States, and a resident of Oneida Mills, in the county of Carroll and State of Ohio, have invented certain new and useful Improvements in Beaters and Scouring-Cases for Grain-Scouring Machines; and I do hereby declare that the following is a full, clear, and exact description of the invention, which will enable others skilled in the art to which it appertains to make and use the same.

This invention relates to an improvement in beaters and scouring-cases to be used on machines for scouring wheat and other grains.

The object is to produce beaters and scouring-cases of such construction that they will be prevented from working smooth, but will at all times present a roughened surface, which is highly essential to good scouring.

With these objects in view, the invention consists in the improved construction and combination of parts of beaters and scouring-cases, as will be hereinafter fully described in the specification, illustrated in the drawings, and pointed out in the claim.

In the accompanying drawings, forming part of this specification, and in which like letters of reference indicate corresponding parts, I have illustrated one form of scouring device fitted up with my peculiar scouring-case and beaters, although the same may be applied to other styles of machines without departing from the spirit thereof, and in these drawings—

Figure 1 is a side elevation of a scouring-machine, part of the casing and scouring-case being broken away to show the beaters in place therein; and Fig. 2 is a detail view of one of the beaters.

Heretofore it has been customary to construct beaters and scouring-cases of a grain-scouring machine of iron or steel. While these answer the purpose very well for a certain length of time the surfaces of these beaters and scouring-cases become worn smooth, and thus fail to scour the wheat thoroughly.

It is the object of this invention to construct the above-named parts of a material which will always present a roughened surface so long as used, and which can never become smooth by use. In order to produce this result, I make the beaters and scouring-

cases out of a composition consisting of fire-brick clay and sand, and mold, stamp, or press it into the desired shape, and then bake it to as great a degree of hardness as possible. Now, it will be seen that as the device is used the fire-clay, being softer than the sand, will wear away, and thus allow the sand to project beyond the surface of the fire-clay, and thus present a surface which will rapidly and efficiently scour any kind of grain.

Referring to the drawings, I have shown one form of a scourer, the casing of which is designated by the letter A. This scourer may be of any desired size and shape, and is provided at its ends with suitable bearing, in which moves a shaft, 1, carrying the arms 2, to which the beaters are secured.

E designates the scouring-case, also constructed of the composition above referred to, and is provided at its upper side with a pipe, 3, in which the grain is fed to the casing, and at its lower side with a discharge-pipe, 4, from which it escapes. The end of the shaft is provided with a pulley, 5, around which passes a belt to a suitable driving mechanism for operating this device.

It will thus be seen that by using the composition above referred to for constructing the beaters and scouring-cases in a grain-scourer all the obstacles heretofore presented by the surface of the beaters and scouring-cases becoming smooth will be obviated; that an old machine may be taken and by simply attaching my improved beaters and scouring-case a machine as good as new will be produced, and that the improvements herein mentioned will lower the cost of the production of scouring-machines.

Having thus fully described my invention, what I claim as new, and desire to secure by Letters Patent, is—

As a new article of manufacture, a beater and scouring-case for grain-scourers, composed of a composition of baked fire-clay and sand, substantially as described.

In testimony that I claim the foregoing as my own I have hereunto affixed my signature in presence of two witnesses.

HENRY WILHELM.
